UNITED STATES PATENT OFFICE.

HEINRICH SULZER, OF WINTERTHUR, SWITZERLAND, ASSIGNOR TO
GEBRÜDER SULZER, OF WINTERTHUR, SWITZERLAND.

CENTRIFUGAL PUMP.

SPECIFICATION forming part of Letters Patent No. 704,144, dated July 8, 1902.

Application filed December 2, 1901. Serial No. 84,303. (No model.)

To all whom it may concern:

Be it known that I, HEINRICH SULZER, engineer, a citizen of the Swiss Republic, residing at 10 Rychenbergstrasse, Winterthur, Switzerland, have invented certain new and useful Improvements in Centrifugal Pumps; and I do hereby declare the following to be a full, clear, and exact description of the invention, such as will enable others skilled in the art to 10 which it appertains to make and use the same.

My invention relates to high-pressure multiple centrifugal pumps driven directly by alternating-electric-current motors, in which a variation of the lift cannot be obtained by 15 varying the number of revolutions.

The invention consists in a special arrangement of a high-pressure multiple centrifugal pump in which the lift may be varied while the pump is driven at a constant number of 20 revolutions.

In the accompanying drawings, Figure 1 is a longitudinal section of a centrifugal pump constructed according to this invention. Fig. 2 is a view in side elevation of a centrifugal 25 pump embodying my invention. Fig. 3 is an end view of the same. Fig. 4 is a broken detail view, in transverse section, of a valve employed in connection with a pump embodying the principles of my invention.

30 There are four pumps $b' b^2 b^3 b^4$ and a corresponding number of connecting-chambers $i' i^2 i^3 i^4$, each of which can be closed to the delivery-pipe B by a suitable valve A, communicating independently with the several 35 pumps through pipe connections $c' c^2 c^3 c^4$, respectively. While the pump is running there is always only one of these chambers open to the delivery-pipe, the rest being closed. When, for example, the full lift of the pump 40 is desired, the chamber i^4 is opened, i', i^2 , and i^3 being closed to the delivery-pipe. In this case the water enters at the intake s and passes through the ducts f' into the first pump b' and the ducts h' into the annular 45 chamber i' , whence it enters pump b^2 through ducts f^2 . The water next passes through ducts h^2 , annular chamber i^2 , and ducts f^3 into pump b^3 and then through ducts h^3 , chamber i^3 , and ducts f^4 into pump b^4 . From here 50 it issues through ducts h^4 and chamber i^4 into the delivery-pipe.

If a smaller lift be desired—for instance, one-half—the chambers i' , i^3 , and i^4 are closed, while i^2 is opened to the delivery-pipe. The water now passes through pump b^2 and chamber i^2 directly into the delivery-pipe without passing through f^3 to b^3 . Similarly the water may be allowed to issue from i' or i^3 . The number of revolutions remains always constant. I do not, however, limit my claim to 60 the special arrangement shown, since it will be readily seen that various arrangements or shapes of ducts and valves would act in the same way without in any way altering the nature of my present invention. 65

The invention is broadly constituted by dividing up a centrifugal pump corresponding to the required maximum power into a suitable number of smaller pumps connected in series and by connecting every single pump 70 with the main outlet by a valve which can be closed or opened as the requirements of work may dictate, thus obtaining as many different heights of lift as divisional pumps are provided, though a constant speed is retained. 75

The power consumed by the multiple pump varies with the increase or decrease of the number of pumps through which the water passes and is greatest when the water flows through all four pumps and least when it flows 80 through the first pump only.

Having now particularly described and ascertained the nature of my said invention and in what manner the same is to be performed, I declare that what I claim is— 85

A centrifugal pump adapted to be driven at a constant speed and comprising a plurality of pump-sections arranged in series relation with respect to each other, each pump-section communicating independently with the outlet, whereby by opening one or the other of such communications the lifting power of the pump may be varied without varying its speed, as and for the purpose set forth. 90

In witness whereof I have hereunto set my 95 hand in presence of two witnesses.

HEINRICH SULZER.
